UNITED STATES PATENT OFFICE

THEODORE BUMANN, OF LITCHFIELD, ILLINOIS; CAROLINE BUMANN EXECUTRIX OF
SAID THEODORE BUMANN, DECEASED.

RAZOR-STROPPER.

1,113,407.

Specification of Letters Patent. Patented Oct. 13, 1914.

Application filed September 26, 1913. Serial No. 792,001.

To all whom it may concern:

Be it known that I, THEODORE BUMANN, a citizen of the United States, residing at Litchfield, in the county of Montgomery and State of Illinois, have invented certain new and useful Improvements in Razor-Stropers; and I do declare the following to be a full, clear, and exact description of the invention, such as will enable others skilled 10 in the art to which it appertains to make and use the same.

This invention is a razor strop, of that type wherein the blade is held within a clip which is automatically moved to and fro 15 by tension on the strop as the latter is moved in one direction or the other, and the object of the invention is to improve a strop of this kind.

This object is carried out by constructing 20 the device as hereinafter more fully described and claimed, and as shown in the drawings wherein—

Figure 1 is a central vertical sectional view through this device in use, and Fig. 2 25 is an end elevation thereof. Fig. 3 is a cross section taken at right angles to the section line of Fig. 1. Fig. 4 is a perspective detail of the razor clip. Fig. 5 is a perspective detail of the rocking member. Figs. 30 6, 7, and 8 are plan views of blanks as will be referred to hereinafter.

The first member of this device is a main frame formed in two parts, stamped from sheet metal, and the blanks from which these 35 parts are made are best shown in Figs. 6 and 7. The body blank is bent into U-shape so that it has three panels or sides, and one of these numbered 1 is by preference solid and forms the closed side of the frame, its upper 40 end being provided with tangs 2; the second side is cut out so as to form three bars 3, 4, and 5 extending across the bottom of the frame, and the intermediate bar has upturned lips 6 pierced with openings 7 for a 45 purpose to appear; and the third side 8 has a large hole 9 through its center and at its upper end a pair of tangs which I have numbered 2 because they are like those on the first panel or side. The other part of the 50 frame is a top plate 10 whose ends are turned downward in lips 11 which overlie the upper ends of the side panels and are pierced with eyes through which said tangs are passed, after which the tangs are bent over to hold

the frame-parts together. This top-plate also 55 has two upstruck tongues 13 pierced with registering holes 14 to receive a hook H by which the entire stropper may be held while the hook is seated in some object not necessary to illustrate. Within the frame as thus 60 constructed is the second or rocking member, also by preference stamped from sheet metal, and the blank from which this member is made is best seen in Fig. 8. It also 65 is of U-shape, but inverted, its head or body portion 20 underlying the top plate of the main frame and having lips 22 turned downward along its sides for a purpose to appear. The ends of this part are bent downward into arms 23 whereof that numbered 23 70 lies inside the solid panel 1 and that numbered 24 lies inside the opposite panel and is provided with a large hole 25 registering 75 with the hole 9 above described; and under the head passes a pivot rod 21 which extends through the arms 23 and 24 and the end panels 1 and 8 of the frame.

The third member is the razor clip which is by preference made of two like pieces of sheet metal 30 having trunnions 31 at their 80 extremities which are journaled at 31' in the lower ends of the arms 23 and 24, depending tongues 32 which are movably mounted between the upturned lips 6 on the central cross bar, and two upstanding lips 85 33 bent inward toward each other and adapted to removably hold the razor blade R; and the two pieces are held close together by means of rivets 34. By preference 1 pass a leaf spring 35 through the eyes 7 in the 90 lips 6 and bend its arms upward as at 36 on opposite sides of the razor clip, which latter is disposed loosely between said arms. All parts are suitably ornamented, and their 95 proportions and exact details and construction are not essential.

In use, the registering holes on the main frame are engaged with a hook H as shown and a razor strop S is passed upward between the bars 3 and 4, then over one lip 100 22 and across the head 20 of the rocking member, thence down over the opposite lip 22 thereof, and finally between the remaining bars 4 and 5 of the frame, and the ends of this strop are to be grasped by the hands 105 of the operator and drawn upon alternately so that the body of the strop will be reciprocated through the device in a manner which

will be clear. The razor blade R is then passed through the registering holes in one panel of the frame and in one arm of the rocking member and inserted into the clip, 5 where it is held between the spring lips 33. The operator then grasps the ends of the strop and reciprocates it in a manner which will be understood, and at each draft one stretch of the strop draws against its lip 22 10 and moves the rocking member where it is pivoted in the frame so that the lower end of the rocking member moves the trunnions of the clip, whereas the lower extremity of the clip is held between the lips 6 in the 15 lower portion of the main frame and cannot move. The result is that the upper portion of the clip, which is where the lips 33 hold the razor R, is thrown away from the descending stretch of the strop and the edge 20 of the razor is borne against the ascending stretch thereof so that the latter is wiped across it and the razor is sharpened or stropped. The presence of the spring arms 36 prevents the clip from being thrown too 25 far outward or the rocking member swung so far to one side or the other that the lower end of the clip would be disengaged from the lips 6. After this blade has been sharpened it may be removed through the large holes 30 in the end of the device, and another blade substituted. Obviously the stropper is capable of sharpening any blade which may be passed through these holes and held within the clip, and for this purpose the size of the 35 stropper should be such as to accommodate it to rather long blades if it is intended that such are to be treated.

What is claimed as new is:

1. In a razor stropper, the combination 40 with a suspended frame; of a rocking member pivoted at its upper end therein and having lips at opposite sides of its pivot, a strop passing over said upper end and both lips, and a razor-clip pivotally mounted 45 within the lower end of said rocking member and having lips at its upper end for grasping the razor, its lower end being movably engaged with the bottom of said frame.

2. In a razor stropper, the combination 50 with a suspended frame; of a rocking member pivoted at its upper end therein and having lips at opposite sides of its pivot, a strop passing over said upper end and both lips, a razor-clip having lips at its upper 55 end for holding the razor-blade, a pendent tongue at its lower end, and trunnions between said lips and tongue pivoted in the rocking member, and a pair of lips upstanding from the bottom of the main frame and 60 between which said tongue is loosely mounted.

3. In a razor stropper, the combination 65 with a suspended frame; of a rocking member pivoted at its upper end therein and having lips at opposite sides of its pivot, a

strop passing over said upper end and both lips, a razor clip having lips at its upper end for holding the razor blade, a pendent tongue at its lower end, trunnions between said lips and tongue pivoted in the rocking 70 member, a pair of lips upstanding from the bottom of the main frame and loosely receiving said tongue, the lips being pierced with eyes, and a spring mounted through said eyes and having upstanding arms loosely 75 embracing said clip, for the purpose set forth.

4. In a razor stropper, the combination with a main frame whose bottom panel is divided into three bars, and a pair of upstanding lips on the intermediate bar; of a rocking member pivotally mounted within said frame, and having a head, a strop passing over the head of said member and on opposite sides of the intermediate bar, and 80 a razor holding device pivotally mounted in said rocking member, the latter having its end disposed between said pair of lips.

5. In a razor stropper, the combination with a main frame consisting of a top plate, 90 two side panels whereof one has a large hole for the passage of the razor blade, and a bottom panel having a pair of upstanding lips; of a rocking member including a head underlying the top of said frame and down-turned side plates whereof that adjacent one side panel of the frame is solid and the other has a large hole, a pivot through said plates and the panels of the frame, and a razor-holder journaled between said plates 100 and having means at its upper end to receive a razor blade, the lower end of said holder being loosely disposed between said lips, for the purpose set forth.

6. In a razor stropper, the combination 105 with a main frame whose bottom panel is divided into three bars with upstanding apertured lips on the intermediate bar, of a rocking member pivotally mounted within said frame, a strop passing over said rocking member and on opposite sides of said intermediate bar, a razor clip pivotally mounted in said rocking member, a dependent tongue carried by said razor clip and loosely mounted between said upstanding 115 lips, and a substantially U-shaped leaf spring disposed between the folds of said strop and extending through the apertures in said lips and on opposite sides of said razor clip to limit the outward movement 120 of the latter.

7. In a razor stropper, the combination with a main frame having attaching devices on one end panel and its opposite end panel composed of three spaced bars with two 125 strap-guiding slots between them; of a rocking member having a head pivotally mounted within the first-mentioned end of said frame and parallel arms projecting from the head toward said bars, and a razor 130

clip pivotally mounted between said arms and loosely engaged with the intermediate bar, for the purpose set forth.

8. In a razor strop, the combination with a main frame including an upper end panel, two side panels, and a cross bar connecting the latter; of a rocking member having a head pivotally mounted within said frame and parallel arms projecting from the head toward said bar, said head having lips at its opposite sides, and a razor-clip having trunnions at its sides pivotally mounted in said arms of the rocking member and a depending tongue, and upward lips on said cross bar loosely receiving said tongue.

9. In a razor strop, the combination with a main frame having attaching devices on one end panel and its opposite end panel composed of three spaced bars with two strap-guiding slots between them; of a rocking member having a head pivotally mounted within the first-mentioned end of said frame and parallel arms projecting from the head toward said bars, said head having lips at its opposite sides, a razor-clip having trunnions at its sides pivotally

mounted in said arms of the rocking member and a depending tongue, upstanding lips on the intermediate bar loosely receiving said tongue, said lips being pierced with eyes, and a leaf spring whose center is mounted through these eyes and whose arms are bent upward and loosely inclose the clips, for the purpose set forth. 30 35

10. In a razor strop, the combination with a main frame having suspending devices on one end and strop-guiding devices in its other end; of a rocking member pivotally mounted in the frame adjacent said suspended end and having side arms moving within the end plates of said frame, a razor-clip pivotally mounted between said side arms, and means for automatically oscillating said clip on its pivot as it is 40 45 swung to and fro between said guides.

In testimony whereof I have hereunto set my hand in presence of two subscribing witnesses.

THEODORE BUMANN.
